MEANS FOR FORMING PLAITS

Alexander McD. Hess, Jamaica, N. Y.

Application July 12, 1932, Serial No. 622,047
Renewed August 8, 1933

8 Claims. (Cl. 156—10)

My invention relates to means for forming and retaining plaits in draperies and curtains and the like and also to provide, if desired, means for engaging a curtain rod or the like, and it is my object to provide means by which a variety of plaits of different sizes or styles may be produced and by means of which the plaits may be quickly and easily flattened for cleaning or washing and pressing the draperies.

10 The housewife of to-day does not ordinarily attempt to make up plaited curtains or draperies since this requires an expert workman to produce even plaits, uniformly and centrally spaced one from another.

15 In my device male and female fastening members are mounted on a header tape or strip of suitable material which is sewed to the top portion of a curtain or drapery so that an unskilled person may, by engaging any male fastening member with any female fastening member, create regular and even plaits or folds.

20 In the past the plaits in draperies have been formed by sewing or pinning the material and the draperies would not be easily cleaned or pressed.

25 By the use of my invention a pull on the ends of the drapery disengages the fasteners which results in a flat drapery which may be thoroughly cleaned and pressed.

30 Where the plaits are formed by sewing the design cannot be readily changed unless the old plaits are destroyed and new ones made and stitched. With my invention endless designs may be produced by engaging selected male and 35 female fastener members. In commercial use the spacing of the fastening members should be a multiple of the width of the curtain materials so that the plaits will be centralized.

35 The ease with which the plaits can be removed 40 permits the smoothing out of the curtains in storing them away. If stored while still plaited the curtain material sometimes cracks at the plait edges.

In order to create plaits with stiff, straight lines 45 my header strip should be made of heavily sized fabric or the like.

The present method of hanging draperies or curtains is generally by means of curtain pins and due to the looseness of insertion the heading 50 sags. My invention contemplates the use of perforations in, or strap-like parts on, the header through which curtain rods may be passed and thus obviate the necessity of perforating the curtain material with pins.

55 In the drawing Fig. 1 is a plan view of my

header tape in its simplest form; Fig. 2 a plan view of a modified form of header tape with curtain rod retaining slots or straps; Fig. 3 a further modification of my header tape wherein the slots are provided with soft metal grommets; Figs. 4, 60 5 and 6 show edge views of some of the plaited effects which may be produced by the use of my invention.

In its simplest form my header strip comprises a tape 1 of fabric or any other suitable material 65 provided with aligned female fastening members 2 and male fastening members 3 alternating and equally spaced. I am aware that male fastening members have been arranged on one tape and female fastening members have been arranged 70 on a separate tape for the purpose of uniting two parts of a garment or the like, but so far as I am aware I am the first to alternately arrange both male and female fastener members on the same tape so that any selected male member may 75 be engaged with any selected female member to form plaits.

This header tape, with the fastener members mounted thereon is sewed to the upper portion 80 of a curtain or drapery. The selected fastener members are then engaged and regular, evenly spaced plaits are formed.

As shown in Fig. 2 the header tape is in the form of a strip of stiff material 4, such as heavy buckram, provided with slots 5—5—5—5, which 85 leave strap-like parts 6—6—6—6 of the material between the slots. The female fastening members 2 and the male fastening members 3 are secured to the header strip as shown and may be engaged to form the desired plaits. A curtain 90 rod 7 may then be passed through the slots 5 and between the strap-like parts 6 to hang the drapery.

In Fig. 3 I have shown a modification wherein 95 an upper and a lower line of fastening members is used and the slots have grommets 7, made of soft, easily bendable metal or the like, secured thereto. When the male and female fastening members are engaged to form plaits these grommets may be bent on their longer axes to form 100 stiffeners for the plait edges.

In some cases, as in shop made draperies, it 105 may be desirable to mount the male and female fastening members directly on the drapery material itself without the connecting or intervening tape or strip, and such use is within the scope of my invention.

While I have shown male and female fastening members of the ball and socket type I do not limit myself thereto as other fastening devices may be 110

substituted therefor without departing from my invention.

I claim:

5. A tape provided with a plurality of openings longitudinally arranged, a soft grommet in each opening, and male and female fastening members secured to said tape, said male and female fastening members alternating and adapted to be engaged one with another for the purpose set forth. 80
10. A tape and male and female fastening members secured to said tape at spaced intervals, the said male and female members alternating, said members being adapted to be engaged one with another for the purpose set forth. 85
15. A tape provided with a plurality of openings longitudinally arranged, and male and female fastening members secured to said tape, said male and female fastening members alternating and adapted to be engaged one with another for the purpose set forth. 90
20. A tape provided with a plurality of openings longitudinally arranged, and male and female fastening members secured to said tape each in a line between openings therein, said male and female fastening members alternating and adapted to be engaged one with another for the purpose set forth. 95
25. A tape provided with a plurality of openings longitudinally arranged, a soft grommet in each opening for the purpose set forth. 100
